UNITED STATES PATENT OFFICE.

PHILIP H. JONES, OF LUTCHER, LOUISIANA, ASSIGNOR OF ONE-HALF TO
RODNEY P. WOODS, OF LUTCHER, LOUISIANA.

POISON-INDICATOR.

No. 823,873.

Specification of Letters Patent.

Patented June 19, 1906.

Application filed March 1, 1906. Serial No. 303,721.

To all whom it may concern:

Be it known that I, PHILIP H. JONES, a citizen of the United States, residing at Lutcher, parish of St. James, State of Louisiana, have invented certain new and useful Improvements in Poison-Indicators; and I do hereby declare the following to be a full, clear, and exact description of the invention, such as will enable others skilled in the art to which it appertains to make and use the same.

This invention relates to improvements in devices for indicating the contents of bottles, and is especially designed for use as a poison-indicator.

To more fully disclose the invention, reference is had to the accompanying drawings, illustrating a practical embodiment of same, the particular features of novelty being succinctly pointed out in the claims.

Referring to the drawings, in which like numerals indicate the same parts in both views, Figure 1 is a fragmentary view in longitudinal section through a bottle and cork stopper, showing the signaling device in elevation; and Fig. 2 is a plan view of the device applied to a bottle.

In the drawings the device is illustrated as comprising a horizontal plate or member 1, adapted to be affixed above the cork, and a vertical plate or member 2, carried by said horizontal plate and adapted to contain an indicating-label. The plate 1 is of a size sufficient to extend peripherally beyond the neck of the bottle and is preferably circular and provided with a plurality of peripheral teeth or points 3. The plate 1 may be affixed above the cork in any suitable way—for instance, as shown in the drawings—wherein 4 designates a fastening-pin integral with the lower face of the plate 1. The label-plate 2 may also be of any suitable construction, but is preferably of the form indicated in Fig. 1, wherein the edges of the plate proper taper upwardly and finally merge into a sharp pin or finger 5.

In operation when a bottle 6 contains a poisonous or other injurious ingredient upon the cork 7 being placed therein the affixing

pin 4 is forced down into the cork, so that the horizontal or protecting plate 1 is detachably superposed thereon, the peripheral teeth 3 extending laterally beyond the neck of the bottle.

The label indicating the contents of the bottle may be pasted or stamped on either or both flat faces of the label-plate 2.

When the device is affixed to a bottle, it will be obvious that the cork may not be extracted until after the indicating means has been detached therefrom, suitable warning being given by the sharpened projections or teeth 3 or by the sharpened finger 5, which latter is particularly effective when groping for a bottle in the dark.

It will be observed that with the above device it is practically impossible for a person to unintentionally consume the contents of the bottle without first having his attention directed to the fact that the bottle contains dangerous ingredients and that the label should be inspected before using.

Having thus described the invention, what I claim is—

1. An indicator for use in connection with a stoppered receptacle, comprising a peripherally-toothed circular protecting-plate and means for detachably securing same above said stopper, and a label-plate superposed on said protecting-plate, substantially as described.

2. An indicator for use in connection with a stoppered receptacle, comprising a circular protecting-plate provided with peripheral teeth adapted to project laterally of the receptacle, and an affixing-pin carried by said plate adapted to be inserted in the stopper of said receptacle, and an integral label-plate superposed on said protecting-plate and provided with a sharpened finger, substantially as described.

In testimony whereof I affix my signature in presence of two witnesses.

PHILIP H. JONES.
